UNITED STATES PATENT OFFICE.

THOMAS HARLEY AND ROBERT G. LONG, OF LAWRENCE, KANSAS, ASSIGNEES TO THE
U. S. MECHANICAL DRAFT COMPANY, OF LAWRENCE, KANSAS, A CORPORATION.

FORCED-DRAFT GRATE.

1,083,094.

Specification of Letters Patent. Patented Dec. 30, 1913.

Application filed April 8, 1913. Serial No. 759,687.

To all whom it may concern:

Be it known that we, THOMAS HARLEY and ROBERT G. LONG, citizens of the United States, residing at Lawrence, in the county of Douglas and State of Kansas, have invented new and useful Improvements in Forced-Draft Grates, of which the following is a specification:

This invention relates to improvements in the construction of the bars of grates for use under forced draft or natural draft in the fireboxes of furnaces, locomotives or the like, and especially adapted for burning slack or fine coal, the invention consisting in the construction, combination and arrangement of devices hereinafter described and claimed.

The object of this invention is to provide an improved form of hollow grate bar comprising a lower member and an upper member detachably secured together, the lower member being provided with valves which, when closed, form the bottom and adapt the bar for use under forced draft and when open adapt the bar for use under natural draft and effect the discharge of ashes from within the bar, another object being to effect improvements in the construction of the upper member whereby the same is provided with a series of detachable perforated plates which may be readily renewed when worn and which prevent undue expansion and contraction of the upper grate bar member.

In the accompanying drawings:—Figure 1 is a fragmentary perspective view of a furnace with its upper portion partly broken away and showing an improved forced draft grate constructed in accordance with our invention and arranged in the firebox of the furnace. Fig. 2 is a vertical longitudinal sectional view of the same. Fig. 3 is a detail plan of several of our improved grate bars, showing them arranged in operative relation to each other. Fig. 4 is a vertical longitudinal sectional view of the same on the plane indicated by the line *a—a* of Fig. 3, showing the valves which form the bottom of the grate bars in closed position. Fig. 5 is a similar view, showing the valves in open position. Fig. 6 is a detail plan view of one of the lower grate bar members, with its valves in closed position. Fig. 7 is a vertical transverse sectional view on the plane indicated by the line *b—b* of Fig. 3.

For the purposes of this specification, a portion of a furnace is indicated at 1 in Figs. 1 and 2, which may be of any ordinary well-known construction and has the usual firebox 2 and ash pit 3. The rear wall 4 of the furnace is formed with a supporting flange 5. The front wall 6 is provided on its inner side with a supporting angle bar or flange bar 7. The grate bars 8 are arranged longitudinally between the firebox 6 and the ash pit, the rear ends of their lower members 9 resting on the shoulder 5 and the front ends of their lower members resting on the supporting bar 7.

Each lower member 9 is hollow, open at its front end as at 10, closed at its rear end as at 11 open at its top and also at the bottom and the side walls 12 thereof have their lower portions formed with downwardly converging inwardly inclined bevels 13 which are provided with upwardly opening recesses 14. Each recess is provided in its bottom at its rear end, with a bearing notch 15. Flanges 16 are formed on the upper sides of the lower grate bar members and extend around the same and serve to retain the upper grate bar members 17 in place on the lower members, as will be understood.

In the bottom of each lower member 9 is a series of valves 18 each valve being provided at its rear corners with outwardly projecting journals 19 which are mounted in the bearing notches 15 of the lower grate bar member. The sides and ends of the valves are beveled so that when the valves are closed their beveled side edges fit closely against the bevel shoulders 13 of the lower grate bar member and their beveled ends fit against one another so that the said valves close the bottom of the lower grate bar member and make the same substantially airtight. The rear end of the last valve in the series projects somewhat beyond its journals 19 as shown in Fig. 6 and is narrowed as at 18' sufficiently to enable it to clear the shoulders 13 and thus permit the operation of the valves.

Each valve 18 is provided at its rear end with a downwardly extending arm 20. The lower ends of the arms 20 are pivotally connected to operating bars 21 and all of the operating bars are pivotally connected at their front ends to arms 22 of a rock shaft 23 the said rock shaft being mounted in bearings 310

at the front of the furnace and being provided with an operating lever 25. Hence, by a single movement of this lever all the flaps of all the grate bars are arranged in 5 either open or closed position. A forced draft air duct 26 is arranged in the front of the furnace and is provided at its upper end with a hollow head 27 having reversely tapered and extending arms 28 which arms 10 are provided in their rear wall with openings which discharge into the open front ends 10 of the lower grate bar members 9.

A suitable cut off damper 29 is provided for the forced draft duct and by means of 15 which the forced draft may be regulated or cut off, as desired. Each upper member 17 is hollow, open at its lower and upper sides and closed at its sides and ends and is of a size and shape adapting its lower edge to be 20 fitted on the lower member 9 and engaged and held in place by the flange 16 of said lower member. The upper member 17 is provided at its upper side with cross bars 30, whereby openings 31 are formed and the 25 sides and ends of the said openings are beveled and converge downwardly so that each opening is larger at its upper side than at its lower side. Plates 32 are detachably fitted in the said openings and have their sides 30 and ends correspondingly beveled so that the plates are held in the opening and with their upper sides level with the tops of the upper grate bar members. These plates 32 are provided with draft slots 33 which may 35 be arranged as here shown or otherwise, as may be preferred. In order to hold the plates 32 securely and yet detachably in place in the openings of the upper grate bar members, metallic strips 34 are employed 40 which are secured to the under sides of the said plates at their ends, by bolts 35 and engage the under side of the cross bars 30 of the upper grate bar members. This construction of the upper grate bar members 45 enables them to expand and contract under varying degrees of temperature without becoming unduly warped or injured and greatly reduces the liability of fracture incident to such contraction and expansion, the 50 plates 32 being fitted somewhat loosely in the openings 31 so that either the members 17 or the plates may expand and contract without affecting the other.

When the damper in the forced air duct 26 is closed and the valves 18 in the lower 55 members of the grate bars are open, the furnace is operated by natural draft. When the damper is open and the valves 18 are closed, forced draft from the duct 26 enters the front ends of the lower grate bar members through the openings 10 and passes upwardly through the upper grate bar members and the slots 33 of their detachable plates 32 so that forced draft is supplied to the fuel in all parts of the firebox and on the 60 grate. The ashes drop through the slots 33 on to the valves 18 when the latter are closed. When it is desired to clean the grate bars, this is accomplished by simply opening the valves 18 by the means hereinbefore described, thus causing the valves to dump the ashes from within the grate bars, as will be 65 understood.

We claim:—

1. A hollow grate bar of the class described 75 open at the bottom and having its side walls provided with downwardly converging shoulders and a series of pivotally mounted valves in said bar arranged for vertical angular movement to open or close the 80 bottom according to the position of the valves, said valves having beveled sides to fit between said shoulders when the valves are closed.

2. A hollow grate bar of the class described 85 open at the bottom and having its side walls provided with downwardly converging shoulders each having bearing notches in their upper sides, valves having beveled sides to fit between the said shoulders and 90 beveled ends to close against one another, the said valves being provided with pivoted journals mounted in the said bearing notches and being also provided with downwardly extending rock arms and an operating bar 95 pivotally connected to the said rock arms for simultaneously actuating the said valves to move them to open or closed position.

In testimony whereof we affix our signatures in presence of two witnesses.

THOMAS HARLEY.
ROBERT G. LONG
